UNITED STATES PATENT OFFICE.

GEORGE G. BAILEY, JR., AND JAMES GILBERT, OF BOSTON, MASS.

DESIGN FOR A FONT OF PRINTING-TYPES.

SPECIFICATION forming part of Design No. 11,757, dated May 4, 1880.

Application filed March 15, 1880. Term of patent 7 years.

To all whom it may concern:

Be it known that we, GEO. GARDNER BAILEY, Jr., and JAMES GILBERT, citizens of the United States, and residing at Boston, county 5 of Suffolk, and State of Massachusetts, have produced and invented a new and original Design for a Font of Printing-Types, of which the following is a specification, reference being had to the accompanying representation, 10 forming part thereof.

The description of our new type is as follows: The outline of the letters is blank, the characters being in intaglio. On the lower and right-hand sides is a colored band, succeeded by a blank line cut in intaglio in the face 15 of the type. The letter is thus in bas-relief as well as intaglio. The surface of the type around the letters is on the same plane with the colored bands of the letters, and is marked or stippled with small dots cut in intaglio all about 20 and between the lines or portions of the letters, as in the central oval portion of the O and the D, in the crescent-shaped space of the C, &c. This dark ground dotted with uncolored spots surrounding the letter on all sides, 25 and there being no border on the right and left hand sides, enable us, by placing the

types side by side, to cause the appearance of a continuous dotted or stippled surface, as if the word or sentence printed were a steel engraving, we still retaining the facility of composition afforded by the separation of the letters. 30

Above and below the letters of our design are, respectively, a white intaglio horizontal line, and beyond a colored space marked with short lines, disposed in pairs, which lines do not reach to the horizontal intaglio space, nor, at the extreme outside, to the bounds of the colored space. 35

At the respective right and left hand ends of the lines in the accompanying representation are seen end pieces, which, being fully illustrated in this typographic impression, need not be further described. 40

We claim—

The design for a font of printing-types, as described and shown.

GEORGE GARDNER BAILEY, JR.
JAMES GILBERT.
